DEGASSING APPARATUS

Kenneth C. D. Hickman, Rochester, N. Y., assignor, by mesne assignments, to Distillation Products, Inc., Rochester, N. Y., a corporation of Delaware

Application December 1, 1937, Serial No. 177,552

1 Claim. (Cl. 183—2.5)

This invention relates to improved apparatus for degassing organic liquids and particularly to an improved method and means for thoroughly degassing an organic liquid which is to be subjected to high vacuum distillation.

The usual method of removing absorbed gases from liquids involves vacuum treatment of relatively static films or bodies of the liquid. This procedure is ordinarily employed to remove gases from an organic liquid in order to prepare it for high vacuum distillation. It was thought that if the liquid were subjected to a vacuum corresponding to that which would be used in the distillation, sufficiently complete gas removal would take place. I have found that complete or substantially complete removal of absorbed gases by this method requires an inordinately long period of time. For instance, if a fish oil is exposed to a high vacuum until a pressure of .001 mm. is reached and then sealed in a closed chamber under this low pressure, it will be found that the vacuum in the chamber is soon destroyed by the additional gases which are more or less slowly evolved from the oil.

Organic liquids which must be distilled under high vacuum conditions are of low vapor pressure and consequently have complex molecules of high molecular weight. Such substances are easily oxidized. Other such substances because of their peculiar molecular structure; such as high degree of unsaturation are exceptionally liable to oxidation. For these reasons a method for rapid and complete degassing of such liquids to remove oxygen and other absorbed gases is necessary.

A type of centrifugal apparatus disclosed in U. S. Patent 1,667,139, has been employed to break up emulsions and suspensions such as flotation froth and ore slimes. These materials were subjected to centrifugal force and vacuum, in order to separate absorbed gases and cause rapid settling of solid components. This apparatus can be employed to remove gases from organic liquids in order to prepare them for vacuum distillation, but it is little better than the commonly used method described above. This is due to the fact that all of the degassing chambers are communicating so that the same pressure prevails throughout. It is therefore, difficult to completely degas the liquid to progressively lower pressures.

This invention has for its object to overcome the above difficulties. Another object is to provide improved apparatus whereby organic liq-

uids can be quickly and completely degassed. A further object is to provide an improved apparatus for degassing organic liquids which are to be subjected to high vacuum distillation. Other objects will appear hereinafter.

These and other objects are accomplished by my invention which in general comprises causing the organic liquid which is to be degassed, to pass by centrifugal force and while in attenuated form, through a series of chambers maintained at progressively lower pressures.

In the accompanying drawing I have illustrated an elevation in section of a preferred form of centrifugal degasser in which like numbers refer to like parts. Referring to the drawing reference numerals 1a—1k designate sections of a cylindrical main casing closed at the top and bottom by plates 2 and 3. The joints between these sections are rabbeted as illustrated in order to prevent entry of gas, and may be sealed with a sealing compound. Tie bolts 4 bind the sections together as one rigid unit. Sections 1b—1k are each provided with a downwardly sloping conical plate 5, the central portion of which extends downward to form a bottleneck-like extension 6. Upon each plate 5 is mounted a cylinder of metal gauze 7 which is covered at the top by a plate 8 having a central opening 9. A baffle 10 is mounted upon the under side of each conical plate 5 in such a position as to be in front of the openings of each vacuum conduit 11 connected to each of the sections of the main cylinder.

A shaft 12 extends the length of the casing and is mounted in housings 13 and 14 integral with end plates 2 and 3 respectively. The upper portion of housing 15 has a greater inside diameter than shaft 12, providing an annular space into which a packing material 16 is placed. The upper portion of this annular space is closed by a plate 20 and is connected at diametrically opposite sides to conduits 21 and 22. Conduit 22 communicates with the upper portion of a reservoir 23 integral with plate 2. In reservoir 23 is a centrally mounted float 24 mounted on shaft 25 the lower portion of which serves as a needle valve to control the flow of liquid through valve seat 26 into conduit 27.

A circular plate 28 integral with collar 29 is mounted upon shaft 12 in the area enclosed by section 1a. A series of substantially identical collars 30 and plates 31 are mounted upon shaft 12 at spaced distances corresponding to the several portions enclosed by main casing sections 1b—1k. Collars 30 are provided with re-

cessed portions 32 slightly larger in diameter than the extensions 6 of conical plates 5 and plates 31 and collars 30 are mounted upon shaft 12 in such a manner that extensions 6 of plates 5 extend into this recessed portion in the manner illustrated. Base plate 3 is provided with an integral reservoir 33 which communicates with the inside of the main casing by way of opening 34 and which is connected to a withdrawal conduit 35.

The apparatus is built in sections in order to simplify construction and dismantling operations. In assembling the apparatus base section 3 is set upon a suitable support and shaft 12 is inserted in the housing 14. The lowest collar 30 and plate 31 assembly is then fixed upon the shaft and the lowest conical plate 5, screen 7 and plate 8 assembly is then fixed to the walls of section 1a. Care should be taken to so locate collar 30 that neck 6 extends well into the recess 32, but does not touch the walls thereof. A sealing compound is then applied to the rabbeted top edge of 1a and section 1b is then put in place. The collar 30 and plate 31 of this section are then fastened in place and conical plate and screen, etc., fixed upon the walls of 1b. Each section is built up in substantially the same way and finally top plate 2 is put in place and the whole assembly bound as one rigid unit by bolts 4.

In operating the apparatus conduit 35 is connected to a closed system which may be a molecular or high vacuum still or an evacuated reservoir. Conduit 21 is connected to a supply of the oil or other liquid which is to be degassed and conduits 11 are connected to vacuum pumps and the system evacuated. The oil flows from conduit 21 into the annular space 15 and thence into conduit 22 and reservoir 23. The presence of the oil in space 15 effectively seals the opening through which shaft 20 enters the casing and prevents entry of air. The oil then flows through valve seat 26, at a rate governed by the float and needle valve, into conduit 27 and finally onto the upper surface of circular plate 28. Shaft 12 is caused to rotate and oil flowing onto the plate is thrown off by centrifugal force as a thin film or curtain of droplets, in which form it is effectively degassed. Gases removed at this stage are withdrawn through the conduit 11 connected to section 1a.

The film of oil thrown from plate 28 collects upon the walls of 1a and flows through the screen 7 and along the upper surface of plate 5 into the space between shaft 12 and bottle-neck projection 6, filling the recessed portion 32 in collar 30. The oil then overflows into the space between collar 30 and projection 6 onto the revolving plate 31 from which it is thrown in attenuated form. Particles of oil are prevented from entering vacuum conduit 11 by baffle 10. The oil flows in the same way through each section where further gas removal takes place and finally passes through opening 34 into reservoir 33 and is withdrawn 65 through conduit 35.

Initial degassing takes place in the top sections where relatively large volumes of gas are removed at comparatively high pressures. It is therefore, advisable to have these sections connected 70 to high capacity pumps. In the next sections

smaller amounts of gas will be removed and pumps giving a higher degree of vacuum should therefore be used. In the bottom sections small amounts of gas remain which can be removed only by maintaining a high vacuum and pumps connected to these sections should therefore be capable of maintaining a sufficiently high vacuum to lower the internal gas pressure to the required extent. A plurality of sections can be connected to the same pump or several pumps giving the same degree of vacuum, but pumps giving increasingly higher vacua should be connected to the lower chambers which are to be maintained under successively lower pressures.

When degassing oils for molecular or high vacuum distillation it is desirable that the internal pressure of gas absorbed in the oil be reduced to approximately, or below, the pressure which is to be employed in the distillation. The pumps connected to the last stages such as 1a and 1b should therefore be capable of maintaining such a pressure which usually will be below .1 mm. and preferably below .05 to .001 mm. Such a complete degassing is particularly important with oxidizable compounds such as vitamins, because if oxygen absorbed from the air remains in the oil in material amounts it will cause oxidation and destruction of the sensitive material when it is heated in the vacuum still.

It will be apparent that many changes can be made in the above described apparatus without departing from the spirit or scope of my invention.

The procedure can be employed to degas organic liquids in general and is of particular advantage for degassing low vapor pressure organic liquids such as cod-liver, halibut liver, linseed oil, hydrocarbon oils, etc., which tenaciously retain absorbed gases. The invention is of particular value for degassing all substances which are to be subjected to high vacuum or molecular distillation. The rapid and complete degassing, which is possible, reduces the problem of maintaining a high vacuum in the still and greatly reduces thermal decomposition and oxidation of easily decomposable substances such as are usually distilled under such conditions.

I claim:

Apparatus for degassing an organic liquid which comprises in combination an approximately vertical, cylindrical casing, a plurality of spaced conical partitions mounted upon the inside wall of the casing, whereby the casing is divided into a plurality of separate chambers, a vertical rotatable shaft passing through the center of the partitions and extending the length of the casing, a plurality of horizontal discs, fixed upon the shaft, each disc being located in a different chamber formed by the said partitions and in spaced relation thereto, sealing means between each partition and the shaft whereby liquid can flow from the upper surface of each partition and thence directly onto the upper surface of the next lowest disc, a conduit directly connected to the space between each pair of partitions whereby the space between each pair of partitions can be highly evacuated, a conduit for conveying liquid onto the surface of the top disc and a conduit for withdrawing liquid from the bottom of the casing.

KENNETH C. D. HICKMAN. 70
